Charles E. Mack, Inventor

By Attorneys # UNITED STATES PATENT OFFICE.

CHARLES E. MACK, OF READING, PENNSYLVANIA, ASSIGNOR OF ONE-HALF
TO JAMES D. BOYNTON, OF READING, PENNSYLVANIA.

REVERSING MECHANISM FOR ENGINES.

SPECIFICATION forming part of Letters Patent No. 726,443, dated April 28, 1903.

Application filed April 19, 1902. Serial No. 103,680. (No model.)

To all whom it may concern:

Be it known that I, CHARLES E. MACK, a citizen of the United States, residing at Reading, in the county of Berks and State of Pennsylvania, have invented certain new and useful Improvements in Reversing Mechanism for Engines; and I do hereby declare the following to be a full, clear, and exact description of the invention, such as will enable others skilled in the art to which it appertains to make and use the same.

This invention relates to an arrangement or combination of features whereby the action of reversing the operation of a steam-engine is accomplished without the use of the usual links and accessory parts.

The present arrangement consists of a four-way valve connected at one point with the steam-supply pipe from the boiler, having two steam connections at right angles thereto, with the steam-chest, and an exhaust-outlet directly opposite said inlet.

It consists, further, in the peculiar arrangement of the slide-valve located in the steam-chest, which valve in this case is made hollow, with two ports on either side directly opposite each other and adapted to register with the inlet and exhaust ports in the steam-chest cylinder in such a manner that the motion of the engine is changed at will by the turning of the four-way valve and allowing the steam to take either of the two courses, one to cause the forward and the other the backward motion.

The operation of the parts is more fully described in the following specification, and the details of construction are clearly illustrated in the accompanying drawings, in which—

Figure 1 is the end view of the cylinder and steam-chest, partly in cross-section, (through X X of Fig. 2,) showing my complete reversing device connected therewith. Figs. 2, 3, 4, 5, and 6 show diagrams of the steam-chest with the valve in all the positions attained during the complete forward and backward stroke. Fig. 7 is a sectional view of the steam-chest. Fig. 8 is a plan view of my complete device, showing the reversing-valve in section. Fig. 9 shows the reversing-valve in section and set to operate in the opposite direction from that shown in Fig. 8. Fig. 10 shows

the slide-valve in detail. Fig. 11 is a sectional view on line X X, Fig. 10.

A is the cylinder of the engine. B is the stem-chest, connected to said cylinder by the usual ports, and in the present case is circular in cross-section, having a central opening b leading into it from its top and a like central opening b' at its side in vertical alinement with the top opening. This steam-chest is formed with two ports b² and b³ on the one side leading to the engine-cylinder and one port b⁴ on the other side directly opposite a point midway of said ports. C is a slide-valve adapted to fit nicely in said steam-chest. It also is mainly circular in cross-section and is formed with a flat upper surface c', thereby forming one side of a steam-space inside of the steam-chest beneath the central opening b and directly above the flat face of the valve. This slide-valve is formed with ports c, two on either side, directly opposite to each other and adapted to register with the ports in the steam-chest.

D is the boiler in which the steam is generated and from which the supply is received. A pipe d, leading therefrom, enters the reversing-valve E at point 1. This reversing-valve E comprises a casing which is substantially dish form and has four equidistant outlets 1, 2, 3, and 4 leading from the central opening or valve-seat. The valve F is adapted to fit in this dish-like casing and is formed with two diametrically opposite grooves f in its periphery, partly encircling its diameter and in alinement with said openings 1, 2, 3, and 4. Each of these ports is adapted to register with two of said openings in the valve-casing at right angles with each other. For instance, in Fig. 8 the pipe d, leading into opening 1, will permit steam entering there to exit through opening 2 at right angles thereto by reason of port f registering with both said openings. In like manner the exhaust-steam from the steam-chest entering the reversing-valve through the pipe d³ and opening 3 will exit at 4. The operation is as follows: Assuming that the engine is to be given motion in a given direction, the valve F is set as indicated in Fig. 8, allowing the steam from the boiler D to enter it at the opening 1 through the pipe d, passing

through the port f and out of the opening 2. A pipe d^2 is connected to said opening 2 and leads to the top central opening b in the steam-chest. The steam entering the steam-chest through this pipe at its top will pass through port b^3 (see Fig. 2) and entering the cylinder A through the port connecting it with the steam-chest and the exhaust will enter the port b^2 in the direction of the arrow 10 and pass through the port c of the valve which registers with said port b^2 and will pass through the hollow valve and out of port c at the other end of the valve and at the opposite side which now registers with port b^4 in 15 the steam-chest. This port b^4 is connected to the reversing-valve E through a pipe d^3 , which leads to the opening 3 in said reversing-valve, and the exhaust-steam entering there will travel through the port f , registering 20 with said openings 3 and 4, and passing out through the exhaust-pipe d^4 , connected to said reversing-valve at the outlet 4.

Should it be desired to reverse the action 25 of the engine, the valve F is given a quarter-turn in the casing E in the direction indicated by the arrow V. This turning of the valve will cause the port f , which now registers with openings 1 and 2 in the casing, to register with the openings 1 and 3, and consequently 30 the port directly opposite it, instead of registering with openings 3 and 4 will then register with 4 and 2. The steam now entering the valve from the pipe d at the opening 1 will exit at 3 (see Fig. 9) and pass 35 through the pipe d^3 and entering the steam-chest at the side opening b' . The steam entering at this point will pass through the port b^4 in the steam-chest and also through the port c of the valve registering with it and 40 pass out through the port c on the opposite side at the other end thereof, which registers with the port b^2 in the steam-chest, and thence into the cylinder, Fig. 6. The exhaust from the cylinder in this case will enter the port b^3 of the steam-chest and exit through the top central opening b , passing 45 through the pipe d^2 , leading therefrom, entering the reversing-valve E at 2, and exit through 4.

50 It will be noticed that my present construction dispenses entirely with the use of the usual links and their connections for accomplishing the reversing of the motion of an engine. In other words, the action in the present case is what is ordinarily termed "direct motion"—that is, the steam is fed directly from the boiler to the slide-valve, and the only interruption in its course from the boiler to the slide-valve in the present case is caused 55 by the reversing-valve E. As just explained, this valve is so constructed that the turning of it in its casing, thereby changing the course

of the steam into the steam-chest, is the only action necessary to reverse the movement of the engine.

The diagrams shown in Figs. 2 to 6, inclusive, show the slide-valve in the different positions it attains in the course of the complete forward and rearward passage therein. In Fig. 2 the arrow indicates the passage of 70 the steam therethrough while the engine is running in one direction. In Fig. 6 the arrows show the direction of the course of the steam therethrough while running in the opposite direction.

75 It is evident that in reversing the action of the engine by means of my valve E the effect is instantaneous, and by reason of the construction of the slide-valve and steam-chest there is no jarring produced by said reversing or changing of the course of the steam.

The present invention is equally applicable to a single or double engine, though of course in the case of the single engine by reason of the single eccentric should the course of the 85 steam be changed by the reversing of the valve E at either end of the stroke—that is, on dead-center—the reverse motion will not be attained simultaneously, as the valve will have to be assisted by a slight move in the 90 direction required.

Having thus fully described my invention, what I claim, and desire to secure by Letters Patent, is—

1. A reversing mechanism for steam-engines comprising steam-chest having top and side inlets, a hollow valve located therein having two ports on either side thereof and a flat top surface, steam connections to said inlets in the steam-chest and a four-way valve connected with said steam connections at opposite sides, said valve having a steam connection to the boiler and an exhaust-outlet therefrom directly opposite said boiler connection. 95

2. A steam-chest comprising a cylindrical 105 body having top and side steam-inlets, two ports on the side opposite said side steam-inlet adapted to lead into the engine-cylinder in combination with a hollow valve having a flat upper surface and two ports on either side 110 thereof directly opposite each other adapted to register with said side inlet and ports in the steam-chest.

3. A hollow slide-valve mainly cylindrical in cross-section having a flat upper surface 115 and two ports cut through the wall thereof directly opposite each other, substantially as and for the purpose set forth.

In testimony whereof I affix my signature in presence of two witnesses.

CHARLES E. MACK.
